UNITED STATES PATENT OFFICE.

CHARLES P. GOLDSMITH, OF NEW YORK, N. Y.

DESIGN FOR A RING.

SPECIFICATION forming part of Design No. 34,394, dated April 23, 1901.

Application filed March 21, 1901. Serial No. 52,243. Term of patent 3½ years.

To all whom it may concern:

Be it known that I, CHARLES P. GOLDSMITH, a citizen of the United States, and a resident of the city of New York, borough of Manhat-

5 tan, in the county and State of New York, have invented and produced a new and original Design for Rings, of which the following is a specification, reference being had to the accompanying drawing, forming a part thereof, in

10 which is represented a perspective view of a ring embodying the features of my design.

The leading feature of the design consists in the representation of opposing buffalo-heads appearing upon the upper periphery

15 of a ring or band.

The minor features of the design consist in

the stone or seal which appears between the two buffalo-heads and in the continuation of the hair of the buffaloes along the periphery of the band or ring as a decoration.

Having thus described my invention, I claim as new and desire to secure by Letters Patent—

The design for a ring herein shown and described.

In testimony whereof I have signed my name to this specification in the presence of two subscribing witnesses.

CHARLES P. GOLDSMITH.

Witnesses:

SIDNEY KINMOUTH,

IRVING J. SCHWARTZ.
